UNITED STATES PATENT OFFICE.

ERD. V. CROWELL, OF TULSA, OKLAHOMA.

TUBING STABILIZER.

Application filed December 18, 1919, Serial No. 345,838. Renewed March 15, 1922. Serial No. 544,039.

To all whom it may concern:

Be it known that I, ERD. V. CROWELL, a citizen of the United States, and a resident of Tulsa, in the county of Tulsa and State 5 of Oklahoma, have invented certain new and useful Improvements in Tubing Stabilizers, of which the following is a specification.

My invention relates to a supporting or stabilizing apparatus for pumping equipment in oil wells, the purpose of my invention being the provision of a stabilizer for the pipe which conducts the oil from the bottom of the well to the surface, commonly known as tubing whereby, the great longitudinal stress which is necessarily imposed on the tubing in its ordinary method of application, and the lateral vibration occasioned by the movement of the pumping valves within the tubing, are eliminated.

20 My invention contemplates the following advantages:

Relieves the tubing of a part or all of the tensile strain.

Provides a potential protection against 25 the tubing dropping should the tensile strain be exceeded.

Prevents the lateral vibration of the tubing which not only adds to its tensile strain but agitates the fluid which causes sand to 30 be carried in suspension and resulting in the rapid wearing out of the pumping cylinder and the valves.

Prevents the pumping cylinder from longitudinal movement occasioned by a similar 35 movement of the valves in the pumping cylinder, thus increasing the capacity of the pump.

I will describe one form of stabilizer embodying my invention, and will then 40 point out the novel features thereof in claims.

In the accompanying drawings:—

Figure 1 is a view, showing in side elevation one form of stabilizer embodying my 45 invention in applied position within a well casing;

Figure 2 is a vertical sectional view of the stabilizer shown in Figure 1;

Figure 3 is a transverse sectional view, 50 taken on the line 3-3 of Figure 2; and

Figure 4 is a perspective view of one of the bolts shown in Figure 2.

Similar reference characters refer to similar parts in each of the several views.

55 Referring specifically to the drawings, and particularly to Figure 1, W designates

a well casing which in the present instance comprises an upper section 15 and a lower section 16 which are connected together at their confronting ends by a coupling member K so as to occupy a perpendicular position within the shafting of the well.

As illustrated to advantage in Figure 2, the coupling member K is in the form of a sleeve and is interiorly provided with an upper screw threaded portion 17 and a lower screw threaded portion 18, such portions being adapted to threadedly engage the outer surfaces of the sections 15 and 16, respectively, as clearly shown in Figure 1. Between the threaded portions 17 and 18 the coupling member K is interiorly formed with an annular channel 19, the upper edge wall of which is inclined inwardly, as at 19^a, while its lower edge wall is projected inwardly at right angles to provide an annular shoulder 19^b, with its lower edge inclined inwardly as at 19^c.

The coupling member K has the same outside diameter as that of a casing coupling, and the same inside diameter as that of the casing on which the device is installed. Thus a wall thickness is provided sufficient to allow for the annular channel 19 without infringing on the diameter of the casing.

Adapted to be inserted within the coupling member K is a cage C which is bored longitudinally, as at 20, to slidably receive the well tubing T. The well tubing T is formed of pipe sections connected by a conventional form of pipe coupling P. The lower end of the well tubing supports a conventional form of working barrel B in which is contained the pump for forcing the oil upwardly through the well tubing, as will be understood. As shown in Figure 2, the opposite ends of the cage C are tapered for the purpose of facilitating the insertion of the cage into the coupling member. Between the tapered portions the cage is formed on its outer surface with an annular groove 21 designed for the reception of a pair of locking members L and L' which are adapted to lock the cage against downward movement within the coupling member, as will be more fully described hereinafter.

As shown in Figure 3, each locking member L and L' is of substantially semi-circular formation and provided with flattened portions 22 adjacent the opposite ends thereof to allow the free passage of gas upwardly through the well casing W. The sides of

the case C may also be flattened for a similar purpose. As shown in Figure 2, each locking member L or L' is recessed intermediate its ends, and on its inner faces to provide 5 a pair of superposed sockets 23 which are adapted to partially house and slidably receive coiled expansible springs 24. The inner ends of the springs 24 bear against the inner wall of the channel 21 and serve to 10 move the members L and L' outwardly from the cage to effect the desired locking function. The movement of the members L and L' under the action of the spring 24 is restricted by a pair of bolts 25 15 which slidably fit within pockets 26 formed in the outer faces of the members. The inner walls of the pockets 26 are formed with suitable openings through which the bolts 25 extend and they have their inner 20 threaded ends secured at diametrically opposite points within the wall of the cage C. As clearly shown in Figure 4, each bolt 25 is formed with a shoulder 25^a which is adapted to abut the cage C to thereby limit the inward movement of the bolt so that it is automatically positioned within the pocket 26 to effect a proper controlling of the locking member L or L'.

As previously stated, the bore 20 of the 30 cage C slidably receives the tubing T, and in its application to the well casing W, it is applied to the tubing at a point above the working barrel B so that when it is engaged with the coupling member K, the 35 working barrel B will be properly positioned, as to elevation in the same, and the coupling P will rest on the cage C to prevent downward movement of the tubing. As the tubing T is moved downwardly to its final 40 position within the well casing, the locking members L and L' slide over the inner surface of the upper section 15. As the cage is moved into the coupling member K, the lower edge of the locking members L and L' 45 abut the flange 19^b and thus prevent further downward movement of the cage so that the same is locked within the coupling member, as shown in Figures 1 and 2. From this arrangement, it will be understood that the 50 tubing T is supported against downward movement as well as lateral movement so that the longitudinal and lateral stresses and vibrations to which the tubing is usually subjected, are absorbed by the cage with the 55 result of reducing the liability of the tubing being broken. Should the tubing be broken at a point above the cage, or should any of the appliances at the top of the well become 60 broken so as to release the tubing, it is manifest that because the coupling P engage the cage C, the dropping of the tube into the well is prevented. It will be understood that the cage can be readily withdrawn upwardly 65 from the coupling K as the locking members L and L' are moved inwardly against the

tension of the springs 24 when engaging the inclined surfaces 19^a of the coupling member, thus permitting the free upward movement of the cage through the coupling member and outwardly of the upper section 15. 70

In operation, the amount of tubing weight allowed to rest on the cage C may be gauged by the amount of tension to which the tubing is subjected at the top of the well. When installing the tubing with the stabilizer, the 75 tubing first rests with full weight, on the cage C, when the tubing will, of course, lean over and bend in long curves in the casing. In order to straighten the tubing in the well so that it will hang true to center, there should be one inch of tension taken out of the tubing for each hundred feet of tubing 80 above the cage C, thus just enough weight of tubing is allowed to rest on the stabilizer to prevent the longitudinal movement 85 of the tubing.

Although I have herein shown and described only one form of stabilizer embodying my invention, it is to be understood that various changes and modifications may be 90 made herein without departing from the spirit of the invention and the spirit and scope of the appended claims.

Having thus described my invention, I 95 claim:

1. A stabilizer for wells comprising a tube receiving cage, a plurality of locking members surrounding the cage and adapted for engaging a portion of the well casing, 100 springs urging the locking members to operative positions, and holding bolts connected to said cage and slidably supporting said locking members.

2. A stabilizer for wells comprising a tube receiving cage, a plurality of locking members surrounding the cage and adapted for engaging a portion of the well casing, 105 springs urging the locking members to operative positions, and holding bolts connected to said cage and slidably supporting said locking members, said holding bolts being formed with heads arranged in the path of travel of and limiting the radial movement of the locking members.

3. A stabilizer for wells comprising a 115 tube receiving cage, a plurality of locking members surrounding the cage and adapted for engaging a portion of the well casing, springs urging the locking members to operative positions, and holding bolts connected to said cage and slidably supporting said locking members, said holding bolts being formed with heads arranged in the path of travel of and limiting the radial movement 120 of the locking members, the ends of the cage being tapered.

4. A stabilizer for well tubing comprising a tube receiving cage having an annular groove, a plurality of arcuate sections received within said groove, having their in-

- ner sides formed with sockets, springs arranged in said sockets and contacting with the inner walls of said grooves for urging the sections outwardly, and holding members slidably connecting said section to said cage and limiting the outward movement of the sections.
5. A stabilizer for well tubing comprising a tube receiving cage having an annular groove, a plurality of arcuate sections received within said groove, having their inner sides formed with sockets, springs arranged in said sockets and contacting with the inner walls of said grooves for urging the sections outwardly, and holding members slidably connecting said sections to said cage and limiting the outward movement of the sections, the end portions of said cage being tapered.
- 10 6. A tubing stabilizer comprising a cage bored longitudinally and formed with a groove on its outer face, locking members slidable in said groove, means for biasing said members radially of said cage, and means for restricting the action of said biasing means.
7. A tubing stabilizer comprising a cage bored longitudinally and provided exteriorly with an annular groove, semi-circular locking members disposed within said groove, springs interposed between said cage and members for biasing the latter outwardly from the cage, and bolts mounted in said cage and slidably associated with said members for limiting the outward movement of said members.
- 15 8. In combination, a well casing, a projection formed interiorly of the casing, and a stabilizer insertable within the casing and comprising a cage, said cage being bored longitudinally and provided exteriorly thereof with a groove, locking members within said groove and movable radially of said cage and adapted to engage said projection, means for biasing said members outwardly from the cage, and means for limiting the action of said biasing means.

ERD. V. CROWELL.
